UNITED STATES PATENT OFFICE.

WILLIAM MISCHLER, OF NEW YORK, N. Y., ASSIGNOR TO FREDERICK H. WEBSTER AND HAWLEY T. WEBSTER, OF BROOKLYN, NEW YORK, A FIRM.

DESIGN FOR A BREAD-TRAY.

No. 37,868.

Specification for Design.

Patented March 6, 1906.

Application filed January 17, 1906. Serial No. 296,577. Term of patent 3½ years.

To all whom it may concern:

Be it known that I, WILLIAM MISCHLER, a citizen of the United States, residing at No. 174 South Elliott Place, borough of Brooklyn, city of New York, county of Kings, and State of New York, have invented a new, original, and ornamental Design for a Bread-Tray or Similar Article, of which the following is a specification, reference being had to the accompanying drawing, forming part thereof.

The drawing shows a plan view of my design.

I claim—

The ornamental design for a bread-tray or similar article, substantially as shown.

WM. MISCHLER.
